UNITED STATES PATENT OFFICE.

WILFRED L. BOON, OF NORTH ATTLEBORO, MASSACHUSETTS.

TUBE-CAPPING MACHINE.

Application filed November 7, 1921. Serial No. 513,402.

To all whom it may concern:

Be it known that I, WILFRED L. BOON, a subject of the King of England, residing at Oldtown, North Attleboro, in the county of Bristol and State of Massachusetts, have invented certain new and useful Improvements in Tube-Capping Machines, of which the following is a specification.

This invention relates to improvements in machines for applying caps to the ends of tubes, more particularly to paper caps to paper tubes, and the object of this invention is to provide in such a machine automatically-operated means whereby the caps may be fed successively to the assembling means, also to provide means for automatically controlling the feed of the tubes to the assembling means and subsequently positioning the caps onto the ends of the tubes.

20 A further object of the invention is to provide a cap hopper with centrifugal means adapted to act upon the caps to tip them up on edge and place their heads against the wall of the hopper and so deposit them successively and in proper operative position into the feed chute to be conveyed to the assembling mechanism.

A still further object of the invention is to provide means for automatically operating the step-by-step feed of the cap and a step-by-step feed of the tubes in time with each other to present a cap and a tube simultaneously to the assembling mechanism.

The invention further consists in the provision of means for applying cement to the extremity of the tube, whereby the cap may be most effectively secured to the tube and also at the same time prevent the cement from coming in contact with the adjacent parts during its transit from the point of application to the assembling position.

A still further object of the invention is the provision of means for entering and expanding a cap into the desired shape and size to readily receive the end of the tube.

A still further object of the invention is the provision of means for automatically

ejecting a misshapened or misplaced cap from the feed-chute.

With these and other objects in view, the 50 invention consists of certain novel features of construction, as will be more fully described, and particularly pointed out in the appended claims.

In the accompanying drawings:

Figure 1 is a side elevation of the machine.

Figure 1^a is a side elevation of the cap-feeding hopper sectioned on line 1^a—1^a of Figure 1.

Figure 2 is an end elevation sectioned on 60 line 2—2 of Figure 1.

Figure 3 is a top view of the machine showing the upper table partially broken away and with the cap-feeding hopper removed.

Figure 3^a is a plan view of a portion of the cap-feeding hopper, illustrating the caps as being positioned to enter the chute.

Figure 4 is a plan view showing the mechanism which is located between the upper 70 and lower tables, the upper table being removed and the lower table broken away to illustrate the lower plunger operating cam.

Figure 5 is an enlarged side elevation showing the upper and lower capping mechanisms, a portion of the upper mechanism being in section.

Figure 6 is an enlarged view illustrating the tube as being forced through the flexible fingers into the cap.

Figure 7 is a section on line 7—7 of Figure 6, showing the bearing wires in the plunger cylinder for preventing the gum on the end of the tube from being deposited in the plunger cylinder.

Figure 8 shows the upper and lower gluing mechanisms and the common drive shaft through which both are operated.

Figure 9 shows a rotatable gluing head in the act of being advanced from the glue-receiving to the glue-applying position during which movement it receives a 90° rotation.

Figure 10 is a top view of the gluing head

illustrating the detent for assisting in locating and releasing the head in its proper operating positions.

Figure 11 is a sectional side elevation illustrating the escapement mechanism for controlling the feed of the tubes and also for retaining the tube while the cement is being applied thereto.

Figure 12 is a view of the tube feed-controlling mechanism sectioned on line 12-12 of Figure 11 and showing one of the glue-applying pads in contact with the end of the tube.

Figure 13 is a perspective view illustrating the lower end of the cap-chute with the cap feed-controlling escapement and the cap-positioning head.

Figure 14 is a view illustrating an ejector for removing a misplaced or misshapened cap from the cap-chute.

This invention comprehends a machine for automatically feeding a cap and a tube to an assembling mechanism and after a cap has been positioned on the tube the latter is then removed to a secondary position where another cap is fed and positioned on the opposite end of the tube, the double capped tube being subsequently discharged from the machine, and the following is a detailed description of one means by which these results may be accomplished:—

With reference to the drawings, 15 and 16 designate two spaced-apart upper and lower tables which carry the operating mechanism, the same being supported on the end frame 17.

Located a short distance above this upper table 15 is a hopper 18 for supplying caps to the upper set of tube-capping mechanism and is shown as being in drum form and as being supported in a fixed position on the tubular standard 19 from this upper table 15. Within this drum-shaped hopper is mounted a rotatable saucer-shaped tray 20 mounted on the shaft 21 to be rotated rapidly from a drive pulley on the shaft 22 through a belt 23 and pulley 24. By which construction a multiplicity of caps 25 may be deposited into this hopper and the rapidly rotating member 20 causes the heavier portion of the cap which is the head thereof to engage the inclined surface 26 of this saucer-shaped rotor 20 and so move upward with its head against the inner surface of the hopper and when in that position the travel of the rotor causes these caps to move forward to engage the inset guide lip 28 and so be led out through the open mouth 27 in the side wall of the hopper into the inclined feed chute 29 whence they roll or slide by their own gravity down to its lower or feed-controlling end best illustrated in Figure 13.

During the time that the caps are being positioned in their feed chute, the tubular

memebrs which are in the present instance of short lengths, are fed from a hopper (not shown) into the tube chute 30, see Figure 11, and in order to control the intermittent successive passage of the tube to the assembling mechanism I have provided a so-called escapement motion which comprises essentially a pair of pins 31 adapted to be positioned in front of the next tube to be fed, and at the same time draw downwardly a pair of clamping fingers 32 by action of the rocker arm 33 which is driven from a shaft 22 (see Fig. 4) through gears 34 through beveled gears 35, shaft 36, beveled gears 37, shaft 42, crank 38, and connecting rod 39 whereby the tube thus positioned is firmly held during the application of glue to the extremity thereof in the manner hereinafter described.

After the glue or cement has been applied to the tube the continued rotation of crank 38 withdraws the pins 31 and simultaneously positions another set of pins 40 in front of the next succeeding tube thereby holding back all of the feeding row of tubes and releasing the single cemented tube to drop into assembling position.

After this cemented tube has been released the pins 31 are again raised and the pins 40 withdrawn permitting the next succeeding tube to enter and be clamped in cementing position and so this action continues to repeat itself intermittently.

The cemented tube when released rolls down its chute 30 and enters the plunger cylinder 43 through an opening 44 in its side.

When the tube is in position in this cylinder it rests upon longitudinally-disposed wires 45, see Figure 7, which prevent the tube from resting directly upon the walls of the cylinder and so effectually prevent the cemented surface of the tube from contacting with the walls of the cylinder to gum the same.

In this cylinder 42 is mounted an endways movable plunger 46 which is provided with a downwardly-extending operating pin 47 engaging the groove 48 of the cam 50. The upper surface of this plunger is provided with a keyway 51 to receive a key 52 to maintain proper alignment during its cam driving reciprocating motion and in the forward end of this keyway I have fixed an adjustable hardened wedge plate 53 for the purpose presently described. As the cam 50 is rotated from the main drive shaft 54 through the worm 55, worm gear 56 and shaft 22, this plunger 46 is advanced, its end engaging that of the tube 57 advancing it on its wire bearings through the spring fingers 58 which are secured in spaced apart relation all about the inner end of the cylinder 43 thus expanding these fingers to engage the flange of the cap 59,

which has been previously positioned by the action of mechanism presently described, the force of which expanding action acting upon the cap support by the cap-head serves 5 to accurately shape the cap to readily receive the end of the tube.

As these fingers are extremely thin they permit the end of the tube to enter the flange of the cap and the continued forward motion of the plunger 46 moves the capped tube and the capping head 60 from the position shown in full lines to that shown in dotted lines see Figure 5, against the tension of spring 61 which acts upon the 10 rod 62 on the outer end of which this capping head is supported.

In order to detain this capping head in its extended position while the plunger 46 is being retracted to release the tube and 20 permit it to roll down the chute 63 into position to receive the next cap, I have mounted a catch member 64 on a fixed collar 65 on this rod 62 which is engaged by the latch 66 which under pressure of spring 25 67 causes its free end 68 to engage the catch 64 and so retain the capping head in extended position for a sufficient period to release its capped tube and also to permit another cap to be fed into assembling position. This cap-feeding mechanism is controlled in its action by a collar 69 on the capping head rod 62 which at its last inward motion is caused to engage the lever 70 and swing the escapement latch 71 outwardly against its spring tension to permit 35 the retained cap to advance one step down the chute to be engaged by the opposite latch finger 71^a, where the cap is ready to be released to drop into the padded hook 72 immediately upon the first return movement of the capping head and its rod which permits the latch 71 to return to normal.

As the plunger 46 is being returned by the continued rotation of the cam 50 the 45 inclined portion 73 of the trip wedge 53 rides under the end of the latch 68 withdrawing its free end from the catch 64 permitting the rod 62 and its capping head to move back under action of the spring 61 50 into position to engage the fresh cap lying in the hook 72. As it is found necessary to move this cap slowly from its first deposited position in the hook forward over the ends of the expanding fingers, I have 55 mounted a piston 74 (see Fig. 5) on the rod 62 to enter a cylinder 75 to form a dash-pot and so check or permit a slow last advancing movement of the capping head, a pet cock 76 being provided for controlling 60 the escape of air from the dash-pot to determine the extent of the cushioning effect.

After a cap has been positioned on one end of the tube as heretofore explained, the tube is released to drop into chute 63 65 where it rolls down to engage the escape-

ment pins 77, here it is arrested and retained by a clamp 78 which mechanism is a duplicate of that above described in the upper capping mechanism. Here is a pad 79 on the second gluing head 80 is caused to engage the end of the tube after which it is released to roll down into the plunger tube 81 to be advanced by the plunger 82 through a set of spring fingers 83 to engage the cap 84 and force back the capping head 85 to 70 the dotted position where it is retained by a pawl 86 engaging a catch 87 when a receding motion of the plunger 82 by the continued rotation of the cam 86 releases the tube with caps on both ends to drop into any suitable receptacle or be conducted away in any suitable manner, not shown.

It is found in practice very desirable from a practical standpoint to apply glue to the very end or extremity of the tube rather than onto any portion of its outer surface so that the glue thus deposited will not come in direct contact with any of the parts over which it passes while in transit to the cap. To accomplish this gluing or cementing operation in a simple and effective way I have provided an upper tank 88 in which glue or cement is deposited and in this tank I rotate a depositing roll 89 with a step-by-step action to deposit the 85 glue upon an endless traveling belt or apron 90 against the face of which the different pads 91 of the glue head 92 are successively pressed. This glue head being rotatably mounted in the slide arm 93 which is moved 95 back and forth in its bearings 94 by means of a pivot rocker arm 95 through the crank 96 which is rotated from the cam shaft 22 through gears 97, shaft 98, gears 99, shaft 100 and beveled gears 101. This slide arm 100 carries a pawl 102 which at each forward motion engages a tooth of the ratchet 103 to rotate the roll 89 with a step-by-step action and which rotating action is communicated to the belt 90 to present a freshly 105 glued supplying surface to the reciprocating glue head pads 91.

As arm 93 moves forward with its glue head the pins 104 in this head successively engage the upstanding finger 105 in the 110 fixed block 106 causing the head to rotate 90° in order to present a freshly charged glue pad to the end of each successive tube. As this slide arm returns the finger is permitted to yield under action of spring 107 115 to allow the next succeeding pin 104 to ride thereover and so be in position to be engaged and rotate the head another step on its next forward movement.

In practice it is found of advantage to 120 provide some means for obtaining and completing a definite movement of the gluing head so as to insure the pads being accurately placed and retained in each glue-supplying position. To accomplish this in 125

a simple and effective way I have provided a squared block 108 on the glue head shaft 109, as best illustrated in Figure 10 and in the bearing bracket I have mounted a spring-
5 pressed plunger 110 adapted to press with sufficient force against the corresponding squared surfaces of the block 108 to insure the completion of each rotating action and retain the head squarely in each operating position.

10 The mechanism for applying glue to the second or uncapped end of the tube, is a duplicate of that just described and is operated from shaft 100 through the pivot arm 118 to reciprocate the slide 119 and so intermittently and successively present pads 79 of the glue-head 80 to the end of the tube 57 prior to its receiving a cap thereon in the manner above described, the glue being supplied to the glue-head from a tank 122, glue roll 123 and belt 124.

15 It is found in practice of importance that the glue or cement should be of the proper tacky or sticky consistency before being applied to the work, to insure which result I have provided the belt 90 which permits the glue to dry somewhat before being taken up by the pads, and then again I permit each pad to rest for one step in the rotation of the 20 head to give the glue further time in which to dry before being applied to the tube, thus obtaining the maximum binding effectiveness, with the minimum amount of glue, then again the thus thickened or tacky glue will 25 not run and drop onto and gum up the adjacent parts which would prevent the accurate working of the machine.

30 It is found in practice that in some instances caps are fed from the hopper into the chute in reverse position and it is also found in some instances that the caps enter the chute in a mutilated condition in both of which cases it is desirable to eject such misplaced or misshapened caps before being advanced to assembling position. To accomplish this in a simple and effective way, I have provided a rotatable brush 111 on shaft 112, which is rapidly revolved from the cam shaft 22 through a belt 113 (see Fig. 2), the 35 bristles of the brush being adapted to enter the opening 115 in the cap-chute 29 to engage the misplaced or misshapened caps and eject them from the chute.

40 I do not wish to be restricted to this particular type of ejecting device as any other suitable means may be employed for accomplishing this purpose. I have applied this ejecting device to both the cap-chute 29 and the cap-chute 116 which latter feeds from the hopper 117 to supply caps for the lower capping mechanism, the construction and action of which hopper is a duplicate of the hopper 18 previously described.

45 The foregoing description is directed solely towards the construction illustrated,

but I reserve the privilege of resorting to all 70 the mechanical changes to which the device is susceptible, the invention being defined and limited only by the terms of the appended claims.

I claim:

1. In a tube-capping machine, the combination with tube and cap-assembling means, of a hopper for receiving a multiplicity of caps, a feed-chute leading therefrom, and means in said hopper for turning 80 the caps on edge and passing them successively into the feed chute.

2. In a tube-capping machine, the combination with tube and cap-assembling means, of a hopper for receiving a multiplicity of caps, and means in said hopper for turning the caps on edge with their heads against the wall and so conducting them into the feed chute.

3. In a tube-capping machine, the combination with tube and cap-assembling means, of a hopper for receiving a multiplicity of caps, and a rotatable member in said hopper having an inclined portion for properly positioning the caps by centrifugal 90 action to feed them successively into the feed chute.

4. In a tube-capping machine, the combination with the tube and cap-assembling means, a hopper for receiving a multiplicity 100 of caps, a rotor in said hopper having means for turning the caps on edge and revolving the same, and a chute having an inturned lip at its mouth for conducting the revolving caps thereinto.

5. In a tube-capping machine, the combination with the tube and cap-assembling means, a feed-chute for conducting the caps successively to the applying mechanism, and means for automatically ejecting an improperly positioned cap from said chute.

6. In a tube-capping machine, the combination with the tube and cap-assembling means, a feed chute for conducting the caps successively to the applying mechanism, and a rotatable member mounted to engage an improperly positioned cap to eject it from its guide chute.

7. In a tube-capping machine, the combination with the tube and cap-assembling means, a feed chute for conducting the caps to the assembling means, said chute being provided with an opening in its rear wall, and a movable member adapted to reach into said opening to engage and expel misplaced and misshapened caps from said chute.

8. In a tube-capping machine, the combination with means for assembling a tube and a cap, of a feed chute, means for depositing caps successively to be fed through said chute to the assembling mechanism said chute having a sight opening wall through which the advancing of the caps may be observed.

9. In a tube-capping machine, cap-feeding mechanism, a tube-supplying magazine, means operated in time with the cap-feeding mechanism for controlling the successive supply feed of said tubes, a pad operated in time with said supply control for applying cement to the extremity of the tube, and means for applying a cap to the cemented end of the tube as they are presented to each other.

10. In a tube-capping machine, the combination of means for presenting caps in succession to be applied to the end of tubes, means for successively feeding tubes to receive the caps on their ends, a latch member arranged adjacent the path of the feed of the caps and normally checking the successive feed of the caps to capping position, means actuated by the movement of said tube feeding means for operating said latch to release the next succeeding cap after each capping operation.

11. In a tube-capping machine, the combination of a cap feeding mechanism including a discharge chute, a tube feeding means for feeding tubes to the delivery portion of said chute, whereby the tubes and caps may be assembled, an escapement mechanism for controlling the successive feed of the caps in said chute, said escapement mechanism including a rock-shaft having oppositely extending arms, each having a detent adapted to extend in said chute, and means actuated by the movement of said tube feeding means for controlling the action of said escapement to release the caps one at a time to move into assembling position.

12. In a tube-capping machine, in combination of tube and cap-feeding means, a tube and cap assembling mechanism comprising means for supporting a cap in tube-receiving position, a cylinder for receiving the tubes successively, and a plunger in said cylinder for advancing the tube onto the cap; an escapement mechanism for controlling the cap-feed to said supporting means, an escapement mechanism for controlling the tube feed to said cylinder means, and means whereby both escapements are operated in time with each other and with the movements of said plunger.

13. In a tube-capping machine, the combination of a cap-feeding means, a tube receiving cylinder having a lateral entrance opening in the side thereof, means for aligning the caps successively at one end of said tube, means for disposing tubes successively into said cylinder, means for applying cement to an end of the tube to be capped, a plurality of longitudinal disposed guide wires arranged about the inner periphery of said cylinder for supporting the tube out of contact with the inner surface of the cylinder, and a plunger of said cylinder for

advancing the tubes through one end of the cylinder into engagement with said caps.

14. In a tube-capping machine, an assembling guide, means for feeding a plurality of caps successively to said guide, a reciprocable capping head for advancing the caps, as fed, toward said guide, means for feeding tubes successively to said guide as the caps are presented to the latter, tube-advancing means for moving the tube and cap to assemble engagement and for causing said capping head to recede to tube discharging position, means for retaining said capping head in discharge position while the tube-advancing means recedes from discharging position, and means on said advancing means for releasing said capping head during its receding movement, whereby the capping head engages the next successively fed cap and moves it to assembling position.

15. A tube-capping machine, as set forth in claim 14, further characterized by a second guide member arranged to have the opposite uncapped ends of the discharged tubes presented thereto, a second capping head for advancing successively fed caps to said second guide, and tube-advancing means arranged to move said tubes into assembling engagement with said caps and to move the tubes and second capping head to tube discharging position, substantially as set forth.

16. In a tube-capping machine, a tube receiving cylinder means for feeding tubes successively into said cylinder, means for successively feeding caps to one end of said cylinder, a reciprocable capping head for moving each cap, as advanced, in assembling position at said end of the cylinder, a plunger in said cylinder for moving said tubes through said end thereof into assembled engagement with said cap and to move said capping head to recede from its assembling position to a tube discharging position, means for locking said capping head in its tube discharging position, means on the plunger for releasing said capping head on its return movement from tube discharging position.

17. In a tube-capping machine, an assembling guide, means for feeding tubes successively to said guide, means for feeding caps successively to said guide, a reciprocable capping head for advancing and positioning each cap relative to said guide for an assembling operation, a plunger associated with said guide for advancing the tube toward said cap into assembling relation and to move said capping head therewith, to a tube discharging position, means for reciprocating said plunger, means normally urging said capping head to assembling position, latch means for retain-

ing said capping head substantially in its discharge position, and means on said plunger engageable with said latch means to release said capping head on the return movement of said plunger.

18. In a tube-capping machine, a relatively stationary tube-cylinder, a plurality of guide spring and cap-shaping fingers at one end of said cylinder, operable means for 10 positioning the caps as fed over the ends of said fingers, means for depositing tubes successively into said cylinder and a plunger in said cylinder for advancing the tubes through said fingers into the cap, whereby 15 the expanding of said fingers shapes the cap to receive the tube end.

19. In a tube-capping machine, a set of spring guide fingers, a movable capping head for advancing the caps as fed over 20 the ends of said fingers, means for feeding the tubes successively through said fingers into the caps as presented, the tube advancing means causing said head with its capped tube to recede to tube discharging position.

20. In a tube-capping machine, a set of spring guide fingers, a movable capping head for advancing the caps as fed over the ends of said fingers, means for feeding the tubes successively through said fingers into 30 the caps as presented, said head being adapted to recede as the tube-advancing means move forward causing its capped tube to also recede to tube discharging position, and means for retaining the capping head in 35 discharge position while the tube-advancing means recede to release and discharge the capped tube.

21. In a tube-capping machine, a set of spring guide fingers, a movable capping head for advancing the caps as fed over the 40 ends of said fingers, means for feeding the tubes successively through said fingers into the caps as presented, said head being adapted to recede as the tube-advancing means move forward causing its capped tube to also recede to tube discharging position, means for retaining the capping head in discharging position while the tube-advancing means recedes to release and discharge the capped 45 tube, and means whereby the return movement of said advancing means releases said head to return to cap-engaging position.

22. In a tube-capping machine, a set of spring guide fingers, a capping head for advancing the caps as fed over the ends of 55 said fingers, means for feeding the tubes successively through said fingers into the caps as presented, said head being yieldably mounted whereby the tube advancing means 60 cause said head with its capped tube to recede to tube discharging position, means for retaining the capping head while the tube-advancing means recede to release and discharge the capped tube, means whereby the 65 return movement of said advancing means

releases said head to return to cap-engaging position, and a dash-pot for controlling the movement of said capping head while it is moving the cap over the ends of said fingers.

23. In a tube-capping machine, the combination with a tube and cap assembling mechanism, means for feeding the tubes, means for arresting each tube during its feeding movement, and a cement carrying pad for applying cement to the end of the tube while 70 arrested.

24. In a tube-capping machine, the combination with a tube and cap assembling mechanism, means for feeding the tubes, means for arresting each tube during its 80 feeding movement, means for applying cement to the extremity of the tube while arrested, and a rotatable head carrying a plurality of cement pads adapted to successively deposit cement on the ends of the tube 85 as fed.

25. In a tube capping machine, the combination with a tube and cap assembling mechanism, means for feeding the tubes, a cement receptacle, an endless belt, a roll in 90 said receptacle for depositing cement onto said belt, and means for receiving the cement from said belt and depositing it successively upon the tubes.

26. In a tube-capping machine, the combination with a tube and cap assembling mechanism, means for feeding the tubes, a cement receptacle, an endless belt, a roll in 95 said receptacle for depositing cement onto said belt, and a receptacle head carrying a plurality of pads for successively receiving cement from said belt and depositing same upon the ends of the tubes.

27. In a tube-capping machine, the combination with a tube and cap assembling mechanism, means for feeding the tubes, a cement receptacle, an endless belt, a roll in 100 said receptacle for depositing cement onto said belt, a rotatable head carrying a plurality of pads for successively receiving cement from said belt and depositing same upon the ends of the tubes, and a combined reciprocating and rotatable head member carrying a plurality of pads adapted to successively receive cement from said belt and 110 apply it to the ends of the tubes.

28. In a tube-capping machine, the combination with a tube and cap-assembling mechanism, a rotatable glue head, a plurality of glue pads carried by said head for applying 115 glue to the tube, and means for permitting the glue on the pads to dry for a predetermined period after receiving and before applying the tube.

29. In a tube-capping machine the combination with a tube and cap assembling mechanism, a rotatable glue head, a plurality of glue pads carried by said heads for applying the glue successively to the tubes, and a step-by-step means for rotating said head where- 125

by each pad is caused to rest for a predetermined period after receiving and before applying the glue to the tube.

30. In a tube-capping machine, a relative stationary tube-cylinder, a plurality of guide spring and cap-shaping fingers at one end of said cylinder, movable means for positioning the caps as fed over the ends of said fingers, means for depositing tubes successively into said cylinder and a plunger in

said cylinder for advancing the tubes through said fingers into the cap whereby the expanding of said fingers shapes the cap to receive the tube end, said cap positioning means being movable in the general direction of the advancing movement of said tubes, whereby said tubes move to a discharging position. 15

In testimony whereof I affix my signature.
WILFRED L. BOON.
